MACHINE FOR SURFACE TREATING SHOE PARTS

Charles G. Brostrom, Lynn, Mass., assignor to
United Shoe Machinery Corporation, Paterson,
N. J., a corporation of New Jersey

Application April 1, 1932, Serial No. 602,467

13 Claims. (Cl. 69—1)

This invention relates to improvements in machines for surface treating shoe parts to prepare them, for example, for the reception of adhesive for securing them to other shoe parts. As herein illustrated the invention is embodied in a machine for roughing a surface of the welt and adjacent trimmed edges of the inseamed materials of a welt shoe preparatory to coating those parts with cement for attaching them to an outsole. The machine is adapted for use in practicing a method of roughing shoe parts disclosed and claimed in a copending application, Serial No. 573,923, filed November 9, 1931, in the name of Walter H. Wedger.

One feature of the present invention consists in the combination with means for surface treating the welt of a welt shoe, of means constructed and arranged to support the welt while it is being operated upon. In one illustrated embodiment of the invention the welt support consists of a thin blade-like member which is adapted to project into the welt crease of a shoe in such a manner as to support the welt against the thrust of the surface treating tool (herein exemplified as a rotary roughing wheel) and also to guide the shoe as it is fed past the wheel.

For the purpose of protecting the inseam stitching from being injured by the action of the roughing tool the illustrated welt support and guide is made with an upwardly convex upper surface constructed and arranged to offset upwardly the portion of the welt being acted upon so as to close the stitch-receiving groove in the welt above the line of stitches. In the illustrated machine the construction and arrangement of the welt support are further such as to support the welt in position to be most effectively operated upon by the roughing means while enabling the shoe to be held in such position that the roughing means will act also upon the trimmed edges of the other inseamed materials of the shoe, i. e., the upper and the channel lips or between substance of the insole. In order to facilitate the positioning of the welt support within the welt crease of the shoe, the illustrated welt support is made movable to and from its operative or work supporting position and, as shown, operator-controlled means is provided for retracting the welt support to a position in which it is better adapted to enter the welt crease and for thereafter returning the welt support to operative position.

In another illustrated embodiment of the invention the welt support and guide is in the form of a rotatable disk and means is provided for positively rotating the disk in a direction to feed

the work past the operating tool. As illustrated, also, the welt support is so located relatively to the operating tool that the thrust of the tool will tend to swing the work in the direction in which the work must turn as the operation being performed thereon progresses around the margin of the shoe bottom and thus to insure against any tendency of the shoe to move away from the welt support and thus cause the latter to ride out of the welt crease while the toe portion of the shoe, 10 for example, is being acted upon.

The invention also consists of other novel features of construction and combinations and arrangements of parts hereinafter described and claimed.

The invention will be described in connection with the accompanying drawings, in which

Fig. 1 is a view in side elevation, partially broken away, of the head of a machine embodying the present invention;

Fig. 2 is a top plan view of the machine;

Fig. 3 is an elevational view of the welt support and a portion of the roughing tool showing these parts in operative relation to a shoe;

Fig. 4 is a sectional detailed view on an enlarged 25 scale illustrating the mode of operation of the roughing tool and the welt support;

Fig. 5 is a plan view of the end of the welt support illustrating the manner in which it supports the welt;

Fig. 6 is a sectional view of the welt support taken along the line VI—VI of Fig. 5; and

Fig. 7 is a side elevational view of a portion of the head of a machine embodying an alternative form of welt supporting and guiding means.

Referring first to Figs. 1 to 5, inclusive, the machine therein illustrated comprises a power-driven rotary roughing tool 10, and a work supporting and guiding member 12, hereinafter referred to as the welt support, which is adapted 40 to enter the welt crease of a welt shoe, such as the shoe 14 shown in Fig. 3, to support the welt against the thrust of the roughing tool and to guide the shoe as it is fed past the tool. Both the roughing tool 10 and the welt support 12 are 45 mounted upon a head 16 which is supported upon a pedestal 18.

The illustrated roughing tool 10 is in the nature of a narrow wheel or roll and while, as shown, the roll is of substantial size it is desirable in many 50 instances to employ one of considerably less diameter. Moreover, roughing tools of various types may advantageously be employed in the present machine. For purposes of illustration, however, a roughing tool has been selected of a 55

type in which the roughing element consists of a multiplicity of short wire bristles 26. As shown, the bristles 26 project from a flexible band 28 which encircles a roll 20 that is fixedly secured 5 to a shaft 22 by means of a taper pin 24. The illustrated band 28 consists of a strip of card cloth having the usual closely arranged and slightly bent bristles which project substantially at right angles to the face of the strip and, as shown, the 10 band 28 is secured to the roll 20 by means of a plurality of adjustable clamping studs 30, the bristles 26 having been removed from the band at spaced localities 32 to enable the clamping studs 30 to engage the outer face of the band at 15 those localities and to draw portions of the band into a series of notches 34 in the periphery of the roll. As illustrated, the clamping studs 30 are carried by levers 36 which are pivotally mounted upon one side of the roll 20 and each of which has 20 an inner end portion arranged to be engaged by a cone nut 38 (Fig. 2) that is threaded upon one end of the tool shaft 22 and is adapted to be locked in position on the shaft by means of a check nut 40. The relative arrangement of the cone nut 38, 25 the levers 36, and the clamping studs 30 is such that by turning the nut 38 the levers 36 may be adjusted to increase or diminish the tension exerted by the clamping studs upon the band 28. By this means the tension of the band may be 30 adjusted so that the portions of the band located between the clamping studs will be forced outwardly a short distance away from the periphery of the roll 20 by the action of centrifugal force when the tool is being driven at high speed. In 35 this way an air cushion is provided for the bristles while they are in contact with the work, thus enabling the tool to have a soft, sensitive action upon the work which may be varied in accordance with the character of the material operated 40 upon by adjusting the clamping studs to vary the amount of tension applied to the band 28. The band 28 is held against edgewise displacement relatively to the roll 20 by means of pins 42 which extend inwardly through apertures in the band 45 28. The above-described means for adjustably securing the band 28 to the roll is substantially the same as that employed for a similar purpose in the machine disclosed in my copending application Serial No. 594,529, filed February 23, 1932, 50 and reference may be had to said application for details of construction not fully disclosed herein.

The roughing tool 10 is mounted in the head 18 with provision for adjustment toward and away from the welt support 14 for the purpose of varying the depth to which the bristles are permitted to penetrate into the work and also in order to compensate for the wearing away of the bristles. For this purpose the tool shaft 22 is journaled in a bearing 46 formed in the front end of an arm 55 48 the rear portion of which is mounted to turn upon a sleeve 50 carried by a bracket 52 which is secured, by means of screws 54, to the head 16. The arm 48 is supported by means of a coiled spring 56 the upper end of which bears against 60 the arm and the lower end of which engages a forward projection 58 of the bracket 52, the spring being held in place by means of a rod 60 which is pivoted at 62 to the bracket projection 58 and which extends upwardly through the coils of the 65 spring 56 and through an aperture in the arm 48 and is provided at its upper end with a thumb nut 64 arranged to engage the arm 48 and to serve as a stop to limit upward movement of the arm under the action of the spring 56 and thus 70 to determine the operative position of the rough-

ing tool. Vertical adjustment of the roughing tool may be effected by turning the thumb nut 64.

The roughing tool 10 is driven by means comprising a belt 78 passing over a pulley 80 that is fast on the tool shaft 22 and over a pulley 82 5 that is fast upon one end of a shaft 84 that is journaled within the sleeve 50. The shaft 84 is driven by means of a belt 86 which passes over a pulley 88 affixed to the shaft. The belt 86 is adapted to be driven by means of a suitable pulley upon a power shaft (not shown). The roughing tool is driven in a counterclockwise direction, as viewed from the right-hand side of the machine, in order that it shall have a tendency to urge the work toward the welt support 12. 15

The welt support 12, in the embodiment of the invention illustrated in Figs. 1 to 6, inclusive, is a thin, smooth-edged and smooth-surfaced blade or wing formed at the free upper extremity of a fixed arm 94 which is mounted with provision for 20 a small amount of movement in a vertical plane to and from a working position. The thinness of the blade 12 which supports the welt enables it to extend into the crease between the upper and edge and surface of the blade enables it to support the welt without interfering with the feeding movement of the shoe past the welt support. As 25 shown, the tip of the blade 12 has a circular edge curvature enabling the blade to extend into the bottom of the welt crease even along the shank of the shoe where the edge curvature of the shoe bottom is concave, and facilitating such swinging of the sole in a horizontal plane as is necessary to cause the roughing operation to progress 30 around the toe and other convexly curved portions of the shoe bottom margin. Furthermore, the blade 12 has a spherically convex upper surface adapted to displace upwardly the portion of the welt supported thereby, as shown in Fig. 4, 35 wherein the welt of a shoe which is being operated upon is indicated at 93, the upper at 100, the insole at 102, and the inseam stitching at 104. As indicated, this upward displacement of the welt 40 98 serves to close the groove in the welt in which the inseam stitches 104 are received so that the latter will be effectively protected from injury by the roughing tool. As indicated at 106 in Figs. 5 and 6, the leading edge portion of the welt support 12 is bent downwardly an amount sufficient 45 to insure that the welt support will not be permitted to enter any one of a series of slits or notches, such as the notches 108 shown in Fig. 5, which may be cut inwardly from portions of the outer edge of the welt for the purpose of facilitating the bending of the welt at the toe of the shoe. As the portion of the welt which overlies the welt support is deflected upwardly by the 50 convexity of the welt support, the notches 108 are opened up in such a manner that in the absence of the flange 106, there might be some tendency for the welt support to ride out of the welt crease through one of these notches. Such action, 55 however, is effectively prevented by the presence of the flange 106. The welt support 12 is so located relatively to the roughing tool 10 and is inclined at such an angle as to present the portion of the welt which is to be operated upon to the front of the roughing wheel at a point somewhat below the horizontal axial plane of the latter. With the work held in this relation to the roughing wheel and supported at an angle determined by the angle of the welt support, as 60 best shown in Fig. 3, the operator is enabled to look downwardly upon the work so that he may 65 70 75

conveniently observe the progress of the roughing operation.

The welt support arm 94 is secured to a carrier 110 which is pivotally mounted in the head 16 to enable the welt support to be moved from an operative position, indicated in Fig. 1, to an in-operative position removed a short distance from the periphery of the roughing tool so as to facilitate the positioning of a shoe with the welt supporting and guiding blade 12 projecting into the welt crease. As shown, the welt support carrier 110 comprises a curved arm 112 the upper end of which is secured to a rockshaft 114 and mounted to turn in bearings formed in the head 16. A horizontal rod 116 rigidly secured at its rear end by means of a binding screw 118 to the arm 112 carries at its front extremity a sleeve 120 which supports an angle block 122 to which the welt support arm 94 is secured. The sleeve 120 is split and rigidly secured to the rod 116 by means of a binding screw 124 arranged to clamp the split sleeve to the rod. The angle block 122 is fixedly secured to the sleeve 120 by means of a binding screw 126 which is threaded into the sleeve 120 and extends through a horizontally elongated slot 128 in the block 122, the slot 128 extending at right angles to the rod 116 to permit adjustment of the welt support in a direction crosswise of the periphery 5 of the roughing tool. Preferably the adjustment of the block 122 relatively to the sleeve 120 is such that the point of engagement of the edge of the welt supporting blade 12 with the bottom of the welt crease will be offset relatively 10 to the center of the area of engagement of the roughing tool with the work in the direction toward which the work is being fed, thereby insuring that the thrust of the roughing tool upon the work will tend to swing the work in a counter-clockwise direction (viewed from above) so as to maintain proper engagement of the shoe with the welt support and thus to facilitate the feeding and guiding of the shoe particularly during operations around the toe. This relative adjustment of the welt support and roughing tool may 15 be varied by loosening the binding screw 126. The block 122 is maintained in fixed angular relation to the sleeve 120 by means of a rib 130 on the block which extends into a corresponding groove in the sleeve 120, the rib and the groove extending at right angles to the rod 116 to permit the above adjustment of the welt support. The welt support finger 94 is secured to the block 122 by means of a binding screw 132 which is 20 threaded into the block and extends through a vertically elongated slot 134 in the finger 94. Either or both of the clamping screws 124 and 132 may be loosened to facilitate adjustment of the welt support 12 toward and from the periphery of the roughing tool.

While the work is being operated upon the welt support 12 is maintained in the operative relation to the roughing tool shown in Figs. 1 and 3 by means of a stiff spring 138 which engages the lower end of the arm 112 and normally holds it against the flattened surface 140 of a cam 142 secured to a horizontal rockshaft 144 which is mounted to turn in the head 16. The cam 142 is adapted to be turned by means of a handle 146 secured to the rockshaft to engage the high portion 148 of the cam 142 with the arm 112 to rock the latter rearwardly against the action of the spring 138 so as to swing the welt support outwardly and downwardly a short distance 25 away from the periphery of the roughing tool.

An extension 136 of the handle 146 is adapted to engage a portion of the head 16 to limit the turning movement of the cam 142. As shown, the spring 138 encircles and is partially supported by a rod 150 the front end of which is pivoted at 30 152 to the arm 112 and the rear portion of which extends through a bearing in a thimble 154 which is threaded into the rear portion of the head 16. The thimble 154 provides a housing for the rear extremity of the spring 138 and is provided with 35 a knurled portion 156 by means of which the thimble may be turned to vary the compression of the spring.

In order properly to present a shoe to the action of the roughing tool the handle 146 is first raised 40 to retract the welt support 12 from its operative relation to the roughing tool and the shoe to be operated upon is held bottom upward at substantially the angle shown in Fig. 4, the welt at one side of the heel portion of the shoe being 45 placed over the welt support 12 and the shoe positioned so that the welt support extends into the welt crease into engagement with the bottom of the latter so that it may function to guide the shoe as well as to support the welt as the shoe is 50 fed manually past the welt support and beneath the roughing tool. After the shoe has been positioned as above described the handle 146 is lowered, permitting the spring 138 to return the welt support to operative position. As the shoe is fed 55 50 the support 12 receives the thrust of the roughing tool thus enabling the latter to operate effectively to roughen the exposed surface of the welt. Because of the convexity of the upper face of the welt support the portion of the welt engaged 55 thereby and consequently the portion of the welt which is being operated upon by the roughing tool is deflected upwardly to such an extent as to insure not only that the entire surface of the welt will be acted upon by the tool but also to close 60 the groove or channel in which the inseam stitches are seated to such an extent as practically to cover the stitches and thus to protect them from injury as a result of contact with the bristles of the roughing tool. The shoe is supported 65 by the operator at such an angle with respect to the roughing tool that the latter in addition to roughing the surface of the welt engages and roughs also the trimmed edges of the upper and the trimmed portions of the channel lip or between substance of the insole. As hereinbefore explained, the downwardly curved flange 106 at 70 the leading edge of the welt support insures against any tendency of the welt support to ride out of the welt crease through any one of a series 75 of open notches such as may be formed in the outer edge of the welt at the toe or other convexly curved portion thereof. To provide for 80 steadyng the work and assisting the operator in holding it so that the edge of the welt support 85 will continuously engage and support the welt throughout the full width of the latter, particularly while operating around the toe, a hook-shaped finger hold 158 is secured to the under side of the welt support. This hook-shaped member 158 is adapted to be engaged by one finger of the operator's hand which supports the portion of the shoe being operated upon, thus 90 steadyng the operator's hand and in that way steadyng the shoe. The finger hold 158 is so located, relatively to the welt support and the shoe as best shown in Fig. 3, that the operator, by pulling upon it can keep the edge of the welt support against the bottom of the welt crease, thus 95 insuring proper support of the welt throughout 75.

the roughing operation upon the shoe. Because of the circular edge contour of the welt support the shoe may readily be held in such horizontal angular relation to the plane of rotation of the 5 roughing tool that the latter will have an operative movement at an oblique angle to the direction of work feed such that the force applied to the work by the tool in such movement shall be resolvable into compartments, one of which is in the 10 direction of work feed and the other of which is toward the welt support. In this way the roughing tool may be made to assist in the feeding of the work. Moreover, when the work is thus presented to the roughing tool the periphery of the 15 tool will travel across the face of the welt in a direction oblique to the edge of the welt and to the line of the inseam stitches and thus will have less tendency to open up the stitch-receiving groove in the welt and thus to engage and possibly break or otherwise damage the stitches.

For receiving and carrying away the dust produced by the roughing operation a conduit 160 (Fig. 2) leading to the pipes of a factory suction system is connected at its forward end to a 20 casing 162 which partially encloses the roughing brush 10 but which is open at the front of the machine to expose the operative portion of the brush and the welt support 12. As shown, the 25 upper portion of the casing 162 is made separate from the lower portion and is hinged to the latter at 164 so that it may be swung backwardly to facilitate replacement of the bristles of the roughing tool.

In Fig. 7 there is shown an alternative form of 30 work support wherein the means for supporting the welt against the thrust of the roughing tool comprises a driven feed disk 170. The disk 170 is secured to the rear end of a short shaft 172 which is journaled in the upper end of an arm 174 which extends upwardly and forwardly from 35 a carrier 176. The carrier 176 is similar to the carrier 110 already described although it is somewhat differently shaped to provide a bearing 178 for a power-driven shaft 180 which is connected 40 to drive the welt support disk 170. As shown, the carrier 176 is secured to the rockshaft 114 and is provided with a depending portion 182 which corresponds to the lower end of the arm 112 and is acted upon by the spring 138 and by 45 the cam 142, the construction and operation of which have already been described. The carrier 176 is provided, below the bearing 178, with a split sleeve 184 for receiving the rear extremity 50 of the arm 114. The sleeve 184 is adapted to be contracted by means of a binding screw 186 to secure the arm 114 adjustably to the carrier 176. The shaft 180 is connected by means of a telescoping link 188 and universal joint connections 55 190, 192 with a shaft 194 which is journaled in the arm 174 and has fixed thereon a gear 196. The gear 196 meshes with an idle gear 198 carried by the arm 174 and the gear 198 meshes with a gear 200 which is fast upon the shaft 172 which carries the welt supporting disk 170. The 60 telescoping link 188 permits adjustment of the disk 170 toward and from the roughing tool to accommodate different thicknesses of welts as well as to compensate for the wearing away of the roughing tool. The shaft 180 is driven by 65 means of a sprocket chain 202 which passes over a sprocket 204 on the shaft 180 and is adapted to be driven from any suitable source of power.

Having described my invention, what I claim as new and desire to secure by Letters Patent of the 70 United States is:

1. In a machine for roughing the welt of a welt shoe, the combination with a roughing tool, of a work support constructed and arranged to support the welt of a shoe while the welt is being operated upon by the roughing tool, a spring for yieldingly holding the work support in operative position, and means for adjusting the spring to vary the force exerted thereby upon the work support. 5

2. In a machine for roughing the outsole-receiving face of the welt of a welt shoe, the combination with a roughing wheel having a peripheral roughing surface, of means for supporting the wheel with its axis substantially horizontal, and means constructed and arranged to hold the welt of a shoe against the periphery of the roughing wheel in a position intermediate between the bottom of the wheel and the axial plane thereof to facilitate observation and control of the roughing operation. 10 20

3. In a machine for roughing the outsole-receiving face of the welt of a welt shoe, in combination, a roughing tool, and means for directly supporting the welt of a shoe against the thrust of the roughing tool, the construction and relative arrangement of said tool and said supporting means being such as to enable portions of said tool to move in substantially straight paths across the welt from one edge to the other. 25

4. In a machine for roughing the outsole-receiving face of the welt and adjacent edges of the inseamed materials of a welt shoe, a rotary roughing wheel, a welt support adapted to project into the welt crease of a shoe to support the welt against the thrust of said wheel, the wheel being mounted to rotate in a plane transverse to that of the welt of the shoe, and means for rotating said wheel in a direction tending to maintain engagement of the welt support within the welt crease of the shoe. 30 40

5. In a machine for roughing the outsole-receiving face of the welt of a welt shoe, in combination, a roughing tool, means for directly supporting the welt of a shoe against the thrust of said tool, said means being capable of yielding to accommodate itself to variation in thickness of the work, means for adjusting said tool toward and from said supporting means, and means for moving said supporting means toward and from operative position. 45 50

6. In a machine for roughing the outsole-receiving face of the welt of a welt shoe, in combination, a roughing wheel adapted to have peripheral engagement with the work, means for supporting the welt of a shoe against the thrust of the roughing wheel, and means for adjusting the roughing wheel toward and from the welt support. 55

7. In a machine for surface treating the welt of a welt shoe, in combination, a surface treating tool, a welt support constructed and arranged to enter the welt crease of a shoe to support the welt and guide the shoe as the shoe is fed past said tool, and means adapted to be grasped by the operator to steady the shoe while the shoe is being operated upon, said means being arranged substantially in line with the welt crease of the shoe to facilitate holding the shoe with the bottom of the crease against the welt support. 60 65 70

8. In a machine for surface treating the outsole-receiving face of the welt of a welt shoe, in combination, a surface treating tool, and means for feeding a shoe to advance the welt progressively past said tool, said means being con- 75

structed and arranged to support the welt and also to guide the shoe as the shoe is being fed.

9. In a machine for roughing the outsole-receiving face of the welt and the trimmed edges

5 of the inseamed materials of a welt shoe, in combination, a roughing tool, a welt support comprising a rotary disk adapted to extend into the welt crease to support the welt against the thrust of said tool said support having a spherically convex welt-engaging surface, and means for rotating the disk to feed the work past the tool.

10. In a machine for roughing the outsole-receiving face of the welt of a welt shoe, in combination, a roughing tool, a welt support comprising

15 a rotary disk adapted to extend into the welt crease to support the welt against the thrust of said tool, said welt support being mounted to yield to accommodate variations in welt thickness, and means for

20 rotating said disk to feed the work past said tool, said means including driving connections constructed and arranged to permit yielding movement of said welt support.

11. In a machine for roughing the outsole-receiving face of the welt and the trimmed edges

25 of the inseamed materials of a welt shoe, in combination, a roughing tool, and a welt support adapted to extend into the welt crease to support the welt against the pressure of said tool, said welt support having an upwardly bulging

30 welt engaging surface, said surface being convex longitudinally of the welt to facilitate feeding of the shoe and being convex transversely of the welt to deflect the portion of the welt be-

ing operated upon by the roughing tool to close the stitch channel along the deflected portion of the welt and thus to protect the welt stitches from the action of the roughing tool.

12. In a machine for surface treating the at-

taching face of the welt provided with slits or notches and the trimmed edges of the inseamed materials of a welt shoe, in combination, a sur-

face treating tool, and a welt support adapted to extend into the welt crease and having a con-

20 vex upper surface to support the welt against the pressure of said tool, the convexity of the up-

per surface of the welt support being more pro-

nounced adjacent to the leading edge of the sup-

port to insure that the welt support will receive 15

the slit portions of the welt and guide them to

overlie the support for proper presentation to the treating tool.

13. In a machine for surface treating the at-

taching face of the welt provided with slits or 20

notches and the trimmed edges of the inseamed

materials of a welt shoe, in combination, a surface

treating tool, and a welt support adapted to ex-

25 tend into the welt crease and having a bulging

upper surface for supporting the welt against 25

the pressure of said tool and deflecting the sup-

ported portion upwardly, said welt support hav-

ing its leading edge portion turned downwardly

below said welt supporting surface for preventing

the welt support from entering any one of a 30

series of slits or notches in the welt strip as the

shoe is fed past the welt support.

CHARLES G. BROSTROM.
